MOISTURE TESTER

A. B. Hilton, Laurel, Miss., assignor of one-half
to Grady Tant, Laurel, Miss.

Application January 5, 1949, Serial No. 69,363

1 Claim. (Cl. 175—183)

1 This invention relates to a moisture testing device.

An object of this invention is to provide a testing device by means of which the moisture content of meats or other food products can be determined. In certain food products it is desirable to cook the article until substantially all of the moisture has been eliminated. In the present invention the presence or absence of moisture in the article is determined by projecting a pair of pointed electrodes into the article, the moisture closing an electric circuit to the electrodes, and the degree of moisture in the article being indicated upon a meter, such as a galvanometer, which is interposed in the electric circuit.

The device embodied in this invention embodies a portable unit including a housing with a handle at one end and the article piercing electrodes projecting from the other end, so that the electrodes can be readily projected into the article, whereupon any moisture in the article will form a conductor between the electrodes and thereby close the electric circuit to the meter.

With the above and other objects in view, my invention consists in the arrangement, combination and details of construction disclosed in the drawings and specification, and then more particularly pointed out in the appended claim.

In the drawings,

Figure 1 is a detail side elevation of a moisture testing device constructed according to an embodiment of this invention.

Figure 2 is a sectional view taken on the line 2—2 of Figure 1.

Figure 3 is a detail front elevation, partly in section, of the device with the housing cover removed.

Figure 4 is a sectional view taken on the line 4—4 of Figure 3.

Figure 5 is a diagrammatic view showing the electric circuits embodied in this invention.

Referring to the drawings, the numeral 10 designates generally a housing which may be formed of either metal, plastic or other dielectric material. The housing 10 has mounted on the upper wall 11 thereof a handle 12 secured substantially centrally of the wall 11 by fastening means 13. The housing 10 has projecting from the bottom wall 14 thereof a pair of spaced prongs or electrodes 15 and 16 which are of pointed construction and are adapted in the use of this device to be projected into an article or sample of food such as a piece of meat M or the like of a predetermined quantity, for determining the

moisture content of the article during the cooking thereof.

The electrode 15 is secured in the bottom wall 14 by means of a pair of insulating bushings 17 and 18, and the electrode 16 is secured in the bottom wall 14 by means of a pair of insulating bushings 19 and 20. The electrodes 15 and 16 are spaced a predetermined distance apart and are connected to a normally open electric circuit shown diagrammatically in Figure 5. A conductor 21 is connected at one end to the electrode 15 and is connected to one pole of a battery B or other suitable source of electric current supply.

The battery B is mounted in the housing 10, being secured in a spring clip 22 which is fixed to the rear wall 23 of the housing. As shown in Figure 4 one end of the battery B has a contact 24 engaged therewith, and the other end of the battery B has a second contact 25 engaged therewith. These two contacts 24 and 25 are secured to the rear wall 23 and where the housing is formed of metal the contacts 24 and 25 will be insulated from the wall 23 by conventional insulating means.

A meter 26 is interposed in the conductor 21 and in the present instance the meter 26 is a galvanometer of conventional construction which includes a swinging pointer 27 and a dial or scale 28 across which the pointer 27 is adapted to swing. In the present instance the dial 28 is divided into three zones with one zone 29 thereof bearing the indicia "Wet" and constituting the starting point of the pointer 27, whereas an intermediate zone 30 bears the indicia "Testing period" indicating the moisture in the food M after the food has been at least partially cooked. A third zone 31 bears the indicia "Dry" and the pointer 27 is adapted to swing into the zone 31 when the food has been cooked substantially dry so that very little or no electric current will pass between the electrodes 15 and 16 when these electrodes are projecting into the food article.

A rheostat 32 is interposed in the conductor 21 between the meter 26 and the positive side of the battery B, and a resistor 33 having a predetermined resistance value is interposed in conductor 21 between rheostat 32 and meter 26. The electrode 16 has connected thereto one end of a conductor 34 which is connected at the opposite end to the negative side of the battery B.

A pair of resistors 35 and 36 having predetermined resistance values are also interposed in the conductor 34 between electrode 16 and the negative pole of the battery B to substantially

balance the meter circuit with the normal predetermined resistance of a "wet" sample to be tested. The meter 26 is secured to the rear wall 23 of the housing by fastening means 37, and the housing 10 has mounted on the front thereof a front wall or closure 38 secured by fastening means 39. The face of the meter 26 projects partly through the front wall 38, the latter being formed with an opening 40 through which the meter 26 is adapted to at least partly project. 10

The rheostat 32 includes a knob 41 disposed on the outer side of the front wall 38 which is adapted to regulate the voltage and amount of current flowing from the battery B to the electric circuit and the electrodes 15 and 16.

In the use and operation of this device, the food article M may be initially tested as to moisture content by piercing the article with the electrodes 15 and 16. The moisture in the article M will form a conductor for the electric current and in the initial operation of this device the rheostat 32 is adjusted to match the total resistance of the circuit with the resistance of M so that the pointer 27 will be in the starting zone 29. The article M may then be cooked and periodic testing of the article by projecting of the electrodes 15 and 16 thereinto will indicate by means of the pointer 27 the amount of moisture remaining in the article.

After the rheostat 32 has once been set, this rheostat need not be further adjusted as with the pointer 27 initially in the starting zone 29, the counter-clockwise swinging of pointer 27 during cooking of the article will indicate the reduction of the moisture content by reason of the poor conduction of electric current caused by whatever moisture remains in the article and is disposed between the electrodes 15 and 16.

With a testing device as hereinbefore described, the article can be tested frequently during the cooking thereof and when the pointer 27 swings to the left into the final zone 31 indicative of a maximum allowable resistance the article will be substantially free of moisture. By the term free of moisture is meant a condition of the material of the article tested wherein further removal of moisture is to be stopped just short of a condition susceptible to burning. In the condition termed free of moisture the moisture content will have been reduced to substantially 7 to 8% in which condition the article can be

readily formed into marketable cakes of uniform quality. Article material that has been overcooked becomes powdery in which condition it is unsuitable for forming into cakes for use in industry. 5

I do not mean to confine myself to the exact details of construction herein disclosed, but claim all variations falling within the purview of the appended claim.

What I claim is:

A moisture testing device comprising a housing including top, bottom, end, front and back walls, a pair of spaced insulating bushings in said bottom wall, a pair of electrodes fixed in 15 said bushings and terminating in pointed portions extending a predetermined distance exteriorly of said bottom wall of said housing for insertion in a test sample of a meat product being cooked and having a minimum known resistance, said electrodes being connected in series with a source of electrical energy, a fixed resistor, a variable resistor, and a resistance measuring meter having an indicating arm movable in response to changes in resistance of said 20 circuit, said variable resistor being adjustable to balance the resistance of the circuit with said minimum resistance of the sample, a scale on said front wall traversible by said indicating arm and graduated for indication of three zones representative of wet, testing and dry conditions of 25 the test sample, the extent of said dry zone being materially less than that of said wet and testing zones, movement of said arm from the wet zone being effected by an increase in the resistance of the sample, such increase being effected by decrease in the moisture content thereof above said known minimum and to the dry zone on increase of resistance of the sample to a predetermined allowable maximum resistance.

A. B. HILTON.
